STOVE

Ben M. Rawlings, Chattanooga, Tenn., assignor to
Tennessee Stove Works, Chattanooga, Tenn., a
corporation of Tennessee

Application January 15, 1940, Serial No. 313,938

14 Claims. (Cl. 126—191)

My invention relates to improvements in stove doors, and more particularly to a hinging and latching means, whereby a stove door which covers and conceals the oven and soot openings of a coal or wood stove can be latched and maintained in position when raised to facilitate the easy removal of the contents of the soot chamber.

For the most part, it has been the practice in the prior art to provide the soot chamber with a separate closure which is opened or removed when it is desired to remove the contents therefrom. The practice in the prior art has also been to hingedly mount the door adjacent its lower end on the casing of the stove near the base of the oven, and to provide a panel just beneath the door and behind which is positioned the soot closure or tray, necessitating the removal of the panel each time the soot is to be cleaned out of the stove. This introduces an additional panel in the casing, detracts from the beauty of the stove, increases its cost of manufacture, and destroys the balance of the stove front. These objections are greatly accentuated where the front of the stove has a surface of porcelain enamel. It is further found to be difficult to obtain a freely removable mounting for a lower panel section, and no adequate means can be attached to the panel to facilitate its removal without detracting from the appearance of the stove. Accordingly removal of the panel is rendered very difficult. The use of tools in prying the panel often serves to scar its outer face. In order to properly mount the panel in place additional mounting means must be employed, so that the difficulty in precisely positioning the panel to insure a proper fit is greatly increased.

Applicant with a knowledge of all of these defects in and objections to the prior art has for an object of his invention the provision of a stove having an oven door with an extension that eliminates the soot closure cover panel without essentially altering the other associated elements and their relation to each other, and without increasing the operating mechanism of the door materially, or reducing the ease of operation.

Applicant has as another object of his invention the provision of a door for an oven which when closed projects down over and covers the soot closure as well as the oven door opening, and when open assumes the position of the open door of the conventional stove, exposing the soot closure.

Applicant has as another object of this invention the provision of an oven door of a stove which, in closed position, projects down over the soot closure as well as the opening of the oven, and thus eliminates the soot closure panel with all of its supporting structure and reduces the time and cost of manufacture, removes the danger in scarring a panel when being removed, as was formerly the case, and gives a balanced front for the stove, as well as eliminating the necessity for making a panel and a door in two separate pieces, and fitting them into place.

Applicant has as a further object of his invention the provision of a door latch for maintaining the lower end of the door from projecting over the soot closure when such door is in a semi-closed position to facilitate the removal of the closure and the cleaning of the soot.

Applicant has as a still further object of his invention the provision of an oven door for a stove employing a floating hinge for mounting the door to the stove intermediate the upper and lower edges of the stove door, whereby the closing of the door causes its lower end to ride down over and conceal the soot closure, and when opened to ride up and assume the position of an oven door on a conventional stove.

Other objects and advantages of my invention will appear in the following specification and accompanying drawings, and the novel features thereof will be particularly pointed out in the annexed claims.

In the drawings, Figure 1 is a front elevation of a range embodying one form of my present invention.

Figure 2 is a side elevation of the same range showing my improved door in open position.

Figure 3 is the same side elevation, showing the door partially open, and raised to expose the soot closure.

Figure 4 is a fragmental detail of the stove door, showing my improved construction.

Figure 5 is a detail sectional view of the door on an enlarged scale taken along lines 5—5 of Figure 4.

Figure 6 is a detail sectional view of the door on an enlarged scale taken along lines 6—6 of Figure 4.

Figure 7 is a detail sectional fragmental view 50 of the door on an enlarged scale taken along line 7—7 of Figure 4.

Referring to the drawings in detail I designates the top of a range or stove which stove has a front utility compartment door 2 hinged adjacent one edge of said stove for movement up-

wardly. On the opposite side of the front of the stove, and hinged in like manner, is a combination ash and fuel door 3. Positioned intermediate of said doors is an oven door 4 which when closed normally covers both the oven opening of the stove, defined in Figure 1 by broken lines, and the closure 6 for the soot chamber, also indicated by broken lines, thus eliminating the usual soot closure panel now in general use. Near the upper edge of the outer face of the door 4 is mounted the usual handle 5 for opening the door. The door 4 is mounted upon the stove by means of a floating hinge which includes rods 9-9 pivotally joined to said door on either side thereof adjacent the lower edge, and extend back through the oven and out through the back wall thereof. Portions of the free ends of the rods 9, 9 project on beyond the rear wall of the stove and have disposed thereabout, between the rear wall and the end of the rods, helical compression springs 10-10 which are retained against removal by crosspins 11 which are seated in transverse openings 12-12.

However, if desired, these crosspins may be eliminated and the outer ends of the springs may be inserted in said openings. Mounted on the door at points below the places where the ends of rods 9-9 are pivotally joined to the stove door 4 are rollers 8-8.

Passing through the stove casing above the soot closure 6 are spaced openings 1-1 for the reception of the ends 19-19 of the anchoring element carried by said door for latching it, when in semi-closed position, at a point above the soot closure to facilitate the removal of soot from the chamber.

My improved door 4, shown in Fig. 4 with cover 29 removed comprises a front wall having an upturned circumferential flange defining its outer extremities. Disposed within the flange 13 and mounted upon the inner face of the outer wall are spaced pairs of oppositely faced angle brackets 17-17 and 17-17 adjacent the lower edge of said door. Disposed between the upstanding portions of said brackets 17-17 adjacent their lower ends are rollers 8-8 having portions projecting through the wall of circumferential flange 13, said rollers having openings which register with mating openings in the upstanding portions of brackets 17-17, through which pins 16-16 pass to form a pivot and with which are associated stops 18-18 to prevent the removal of the pins 16-16. Interposed between the upstanding portions of brackets 17-17 adjacent their upper edges are the downwardly curved end portions of rods 9-9 having openings therethrough which register with mating openings in the upstanding portions of the brackets 17-17 and through which are passed pins 15-15 that act as pivots for said rods 9-9, and which are retained against removal by stops 18-18.

Intermediate said pairs of brackets 17-17 and located adjacent the lower end of said door 4 is a cover plate 29 having a projecting flange along either of the short edges thereof through which screws 31-31 are adapted to pass, and to set in openings 30, 30 in the lower wall of door 4 for retaining the cover 29 in position.

Disposed within cover 29 and in sliding relation thereto is a channel member 20 having upturned ends which bear against the inner faces of the sides of the cover 29 and serve to guide the channel member 20 in its movement back and forth from operative to inoperative po-

sition. Mounted on the outer face of the lower end of the channel member 20 is a bearing 28 having a projection which overlaps and is secured adjacent the lower outer face of said channel member 20, the lower end of said bearing being curled to receive the body of a rod or anchoring element having downturned ends 19-19 which are adapted to pass through appropriate openings in the circumferential flange 13 extending along the lower end of the door 4. The operating mechanism for the channel member 20 and associated elements comprises an arm 26 running longitudinally of such door through the central portion and having an end which extends through its upper flange 13 and which may be curved to form a finger 27 to facilitate the movement of the arm. Joined to the lower end of arm 26 and disposed within the flange 13 is a block 21 pivoted intermediate its ends at 23 and adjacent one end to arm 26 at 25 and at the other end to channel member 20 at 22, the lower edge of the cover 29 being slotted to facilitate ready movement of the block 21 which passes into such cover.

Positioned over the inner face of the door 4 is a cover plate 14 having a flange along its edge which overlaps the flange 13, the cover 14 being held in place by appropriate screws.

The operation of the door is as follows:

Starting from the closed position of Figure 1 door 4 overhangs the lower edge of the oven opening and conceals the soot closure thus replacing the soot closure panel. As outward force is applied to the handle 5, the top of the door moves outwardly and the rollers 8-8 move up the face of the wall of the stove and pivots 15-15 move downwardly until the upper face of plate 14 is substantially co-extensive with the bottom of the oven at which point the rollers 8-8 come into engagement with grooves in the lower edge of rods 9-9 and prevent further upward movement. The door will then be maintained in horizontal position.

The door is closed by imparting an initial force to the handle 5 moving the upper edge of such door 4 towards the top of the opening of the oven, so that the rollers 8-8 roll down the face of the front of the stove under the influence of springs 10-10 which tend to urge the door 4 to closed position. As the door reaches its closed position, the rollers have traversed the distance representing the distance of the portion of the front of the stove which is overlapped by the projecting door and the upper edge just overlaps the top of the oven opening.

The door in open position, it will be noted, has moved up to clear the soot closure 6 and will permit the removal of the soot therefrom. However, such door being in horizontal position will greatly hamper the operations necessary for soot removal. Accordingly, it is desirable to have the door moved out of horizontal position to facilitate access to the closure 6.

In order to accomplish this, the door, being in horizontal position, must be closed, but before this operation is begun, the finger 27 is manually pulled outwardly causing more of the arm 26 to move out of the door and imparting a clockwise movement to the block 21 about its pivot 23, which in turn imparts a downward movement to channel member 20 which carries the rod in bearing 28 and projects the ends 19-19 of the rod out through the lower edge of the door and into the openings 1-1 of the front wall of the stove so that as the door is closed, the rollers

are prevented from moving downwardly from the anchoring portions 19-19 and the door assumes a position indicated in Figure 3 as it is moved upwardly. This exposes the closure member 6, and removes the door 4 from interference with the soot removing operations.

When the soot has been removed and the closure 6 reinserted in the stove, the handle is moved downwardly until the door is again in horizontal position, indicated in Figure 2. The finger 27 is then pushed inwardly moving arm 23 downwardly and swinging block 21 about its pivot 23 thus raising channel member 20 with its bearing 28 and rod and removes the ends of such rod 19-19 from the openings 7-7 thus releasing the door so that it may be closed in the manner hereinbefore described.

Having thus described my invention, I claim:

1. A stove of the character described comprising a body, an oven in said body, a soot compartment beneath the oven, a drop door for covering said oven and compartment when in closed position, means hingedly secured to said door for resiliently mounting it from said body, and anti-friction means carried by the door for riding up over the face of said body when it is swung to open position to expose said soot compartment.

2. A stove of the character described comprising a body, an oven in said body, a soot compartment beneath the oven, a door covering said oven and compartment when in closed position, means cooperating with said door to raise its lower end when open to expose said soot compartment and to lower its lower end when closed, and means for maintaining said door in raised position when partially closed.

3. A stove of the character described comprising a body, an oven in said body, a soot compartment beneath the oven, a drop door covering said oven and compartment in closed position and exposing them in open position, means resiliently supporting said door from said body, anti-friction means carried by the lower portion of the door for riding up over the face of said body when it is swung to open position, for bringing the inner face of the door to the level of the bottom of the oven and to expose said compartment.

4. A stove of the character described comprising a body, an oven in said body, a soot compartment beneath the oven, a drop door covering said oven and compartment in closed position, means resiliently supporting said door from said body, anti-friction means carried by the door for riding up over the face of said body when it is swung to open position, the inner face of said door being in coincidence with the bottom of said oven when in open position.

5. A stove of the character described comprising a body, an oven in said body, a soot compartment beneath the oven, a drop door covering said oven and compartment in closed position, means cooperating with said door to raise the lower end thereof when open to expose said compartment and to lower said lower end when closed, means for maintaining the lower end of said door in raised position when partially closed for exposing said soot compartment and means hingedly secured to said door for resiliently mounting it from said body.

6. In a stove, an oven, a soot compartment positioned beneath said oven, a drop closure for normally concealing said oven and said compartment, a handle mounted on said closure, a

floating hinge mechanism for operatively mounting said closure on the front of said stove including arms pivotally joined to said closure and secured through their free ends to the rear of said stove, and means attached to said closure adjacent its lower end to provide rolling engagement with a face of said stove for rolling up the face of the stove to expose said oven and compartment when in open position.

10. 7. In a stove, an oven, a soot compartment beneath the oven, a drop closure therefor, restraining arms pivotally connected to said closure intermediate its ends and joined through their free ends to the rear of said stove, and rollers bracketed to said closure adjacent its lower end for rolling up the face of said stove when said closure is in open position to expose said oven and said compartment.

8. In a stove, an oven and said oven being positioned above the soot compartment, a soot compartment, a closure normally covering said oven and compartment, a handle mounted on the face of said closure, restraining arms pivotally connected to said closure and fastened by their protruding end portions at the rear of said stove by helical compression springs, rollers attached to said closure adjacent its lower end for rolling up with the face of said stove to clear and expose said soot compartment when in open position, and means attached to said closure for manually locking it in raised position to expose said soot compartment.

9. In a stove, an oven and a soot compartment, a closure therefor, a handle mounted on the face of said closure for opening and closing it, rollers attached to said closure adjacent its lower end for rolling engagement with the face of said stove, restraining arms pivotally connected to said closure and fastened by their protruding ends at the rear of said stove by helical compression springs between the rear wall of said stove and the protruding ends of said arms for limiting the distance of travel of the lower end of said closure up the face of the stove, and means attached to said closure for manually locking it in raised position to expose said soot compartment.

10. In a stove, an oven and a soot compartment, a closure therefor, a handle mounted on the face of said closure for opening and closing it, rollers bracketed to said closure adjacent its lower end for rolling engagement with the face of said stove, restraining arms pivotally connected to said closure and fastened by their protruding end portions at the rear of said stove for limiting the distance of travel of the lower end of said closure up the face of said stove, and a manually controlled locking means mounted within said closure comprising pins operatively connected to an arm for engagement in mating openings in the face of said stove for locking said closure in raised position to expose said soot compartment.

11. In a stove, an oven and a soot compartment, said oven being positioned above said compartment, a closure therefor, said closure normally covering said oven and compartment when in closed position, rollers disposed on said closure adjacent and partially protruding from, its lower end to roll up the face of said stove during the opening of said door, restraining arms pivotally connected to said closure and fastened by their protruding end portions by helical compression springs to the rear of said stove, said closure

when in open position clearing said compartment and exposing it.

12. In a stove, an oven and a soot compartment, a closure therefor, rollers mounted on said closure adjacent and partially protruding from its lower end to provide rolling engagement with the face of said stove, restraining arms pivotally connected to said closure and fastened by their protruding end portions to the rear of said stove, a means for locking said closure in position to expose said soot compartment comprising a manually controlled finger, an arm connected thereto and hingedly controlling a block to which is attached a bail with outwardly extending end portions, and openings in the face of said stove for receiving said outwardly extending end portions.

13. In a stove, an oven and a soot compartment, a closure therefor, a handle mounted on the face of said closure, rollers mounted on, and partially protruding from, said closure to provide rolling engagement with the face of said

stove, restraining arms pivotally connected to said closure and fastened at their free ends to the rear of said stove, means for operatively connecting said rollers and said restraining arms to said closure to limit the distance of travel of said closure up the face of said stove, and means for manually locking said closure in raised position to expose said soot compartment.

14. A stove of the character described comprising a body having a base, an oven in said body over said base, a soot compartment between said base and said oven, a drop door extending upwardly from said base for normally covering said oven and compartment when in closed position, means engaged with an intermediate portion of said door for supporting it from said body, and anti-friction means interposed between said body and door to facilitate the travel of the lower portion of said door up the face of said body for clearing and exposing said compartment when swung to open position.

BEN M. RAWLINGS.
